SANDAL

David D. Goldstein, Pittsburgh, Pa.

Application January 3, 1945, Serial No. 571,131

5 Claims. (Cl. 36—11.5)

1

My invention relates to sandals and has particular reference to sandals made of vegetable fibers, particularly of fibers of raffia.

This is a continuation-in-part of my application, Serial No. 510,469, filed November 16, 1943.

I have found that natural fibers of raffia, which is a tropical plant, when treated with steam, can be woven into tight braids which can be used for making sandals, including their soles.

The raffia braids possess strength, pliability and remarkable wearing qualities, comparing favorably with leather and being far superior to other vegetable fibers such as straws. The braids, particularly for the soles, can be made of considerable thickness, still retaining flexibility and light weight.

The braids may be dyed, lacquered or impregnated with suitable compounds before being used for making the sandals.

My invention is more fully described in the accompanying specification and drawing in which:

Fig. 1 is a side view of my sandal partly in section;

Fig. 2 is a top plan view of the same;

Fig. 3 is a sectional view taken on the line 3—3 of Fig. 1;

Fig. 4 is a detailed view of a braid being made of raffia strands;

Fig. 5 is a sectional view of the braid;

Fig. 6 is a similar view of a multiple strand braid.

My sandal as shown in one of its forms in Figs. 1 to 3 inclusive consists of a sole 1 which is preferably made of three layers 2, 3 and 4 of raffia braids, wound flatwise as shown in section in Fig. 3. The braids 5 are woven preferably of three strands of raffia as shown in Figs. 4 and 5 so as to obtain a flat strip of a strong and flexible material. The braids are stitched together at the edges and formed into elongated spirals so that each layer of the sole represents a flat body with rounded edges and without corners. The outer layers 2 and 4 are preferably made of relatively thick braids, the inner layer 3 being made of relatively thin braids, all three layers being stitched together in various places through the middle and at the edges, preferably using un-twisted raffia strands for threads. The lower layer 2 is cut short at the rear and is of reduced thickness as shown in Fig. 1, the thin end 7 being inserted under a shoulder 8 of a heel 9. The heel may be made of any suitable material such as wood, plastic, etc. or it may be also wound of raffia braids. The intermediate layer 3 may con-

2

sist of a single braid at the edges of the sole as shown in Fig. 3.

The upper front or toe portion of the sandal is formed of wide bands 12, 13 which may be made of previously stitched braids, or of braids stitched on the last. The bands are placed across the sole, the ends of the bands being bent inwards and attached to the sole as shown in Fig. 3, preferably by strands 10 passing through the sole and through the ends of the bands 12, 13. Two such bands may be used as shown, one for the instep and the other for the toe of the sandal. An inner sole 11 is placed over the inner ends of the bands.

15 The heel is built up at the rear by placing a suitable wedge 14 made of wood or similar material and placed on top of the sole and covering the same on the outside by a band 15 made of raffia braids. The end portions of the band are trimmed at an angle as shown and attached to the upper edges of the sole as by stitching by raffia strands. The bands are fastened to the heel as by cementing, and attached temporarily until the braids are stitched together.

20 25 An ankle strap 16 is also made of raffia braid and is supported on two pairs of upwards extending braids 17, 18 at the sides of the heel portion 15. One end of the ankle strap is provided with a button 19, the other end having a loop 20 for the button. A plate or "top-lift" 23 made of leather or other suitable material can be attached to heel 9.

30 35 My sandals can be conveniently made on ordinary lasts, by placing the bands across the upper portion of the last and temporarily attaching the bands as by nails or staples, then similarly attaching the sole over the ends of the bands. The bands and the sole are then stitched together, nails or staples removed, and the product removed from the last.

40 45 The braids 1, 2, 3 may be made of several braids each, or of a single wide braid 22 as is shown in Fig. 6.

It will be understood that various features and principles of each of the embodiments of the invention above described or referred to may be utilized or substituted in the other embodiments.

50 55 While the invention has been described in detail with respect to certain particular preferred examples, it will be understood by those skilled in the art after understanding the invention, that various changes and further modifications may be made without departing from the spirit and scope of the invention, and it is

intended therefore in the appended claims to cover all such changes and modifications.

What is claimed as new and desired to be secured by Letters Patent is:

1. A sandal comprising a sole having several layers, each layer being made of flat braids of a fibrous material stitched together edgewise, the bottom layer being cut short at the rear and reduced in thickness, the layers being stitched together; a heel attached to the rear end of the sole having an undercut at the front end, the rear thin end of the bottom sole layer being fitted into the undercut of the heel; and an upper front portion of the sandal made of a band formed of several braids woven from strands of a vegetable material and stitched together edgewise, the ends of the band being bent inwards and attached to the upper side of the sole.

2. A sandal comprising a sole formed of three layers, the top and bottom layers being made of relatively thick braids woven of strands of vegetable fibers, the inner layer being made of relatively thin braid in the form of a ring placed between the edges of the outer layers, the layers being stitched together, the bottom layer being cut short at the rear end and reduced in thickness; a heel attached to the rear end of the sole, the heel having an undercut at the front end, the thin rear end of the bottom layer being fitted into the undercut of the heel; and an upper front portion of the sandal made of several braids of a fibrous material placed across the front portion of the sole, the ends of the braids being bent inwards and attached to the upper side of the sole.

3. A sandal comprising a sole formed of three layers, the top and bottom layers being made of relatively thick braids woven of strands of vegetable fibers, the inner layer being made of relatively thin braid in the form of a ring placed between the edges of the outer layers, the layers being stitched together, the bottom layer being cut short at the rear end and reduced in thickness; a heel attached to the rear end of the sole, the heel having an undercut at the front end, the thin rear end of the bottom layer being fitted into the undercut of the heel; and a layer of a wear resisting material on the heel.

4. A sandal comprising a sole; an upper front portion formed of several braids made of strands of a vegetable material, the braids being placed across the front portion of the sole, the ends of the braids being bent inwards and attached to the sole; a wedge made of a relatively light material placed on top of the rear portion of the sole; and a plurality of braids made of a vegetable material placed on the outside of the wedge, the ends of the braids being attached to the sole.

5. A sandal comprising a sole; an upper toe portion comprising bands made of several braids of vegetable fibers stitched together, the bands being placed across the toe portion of the sole, the ends of the bands being bent inwards and attached to the sole; an upper heel wedge portion comprising bands extending around the heel of the sandal and attached at the ends to the edges of the sole; and additional upper bands attached at the ends to the upper edges of the upper heel band.

DAVID D. GOLDSTEIN.
